UNITED STATES PATENT OFFICE.

ERWIN F. VON WILMOWSKY, DECEASED, LATE OF BOSTON, MASSACHUSETTS, BY EDWIN J. PRINDLE, EXECUTOR, OF EAST ORANGE, NEW JERSEY, ASSIGNOR TO NORSK HYDRO-ELEKTRISK KVAELSTOFAKTIESELSKAB, A CORPORATION OF NORWAY.

ELECTRIC FURNACE AND PROCESS OF HEATING SUBSTANCES UNIFORMLY AND AT A CONTROLLABLE TEMPERATURE.

1,128,640.

Specification of Letters Patent. Patented Feb. 16, 1915.

Original application filed October 28, 1896, Serial No. 610,286. Divided and this application filed April 18, 1914. Serial No. 832,932.

To all whom it may concern:

Be it known that ERWIN F. VON WILMOWSKY, late a citizen of the United States of America and resident of Boston, county of Suffolk, Commonwealth of Massachusetts, did invent certain new and useful Improvements in Electric Furnaces and Processes of Heating Substances Uniformly and at a Controllable Temperature, of which the following is a specification.

The present application is a division of original application Serial No. 610,286, filed October 28, 1896, and includes subject matter erased without prejudice from said original application with the express intention of applying for a separate patent.

This invention relates in general to the treatment of substances electrically, and more particularly to the treatment of gases.

The inventor has found that an arc-furnace in which the materials to be heated are brought directly into the arc and exposed to its influence, has the disadvantage that where the arc happens to pass the contents are overheated and, if in a solid or liquid state, partly volatilized or scattered around, while the particles close by are heated insufficiently or too slowly.

Now, the object of the invention is to heat substances uniformly in an electric arc, at a controllable and (where desirable) at a reduced temperature, and to make the operation continuous. This is accomplished by the means and process hereinafter described.

The invention consists therefore in the novel means and process hereinafter set forth and illustrated in the drawings.

Apparatus for carrying the process into effect is illustrated in the accompanying drawings, and this, as well as the process which is thereby carried out, will be described hereinafter.

In the drawings, Figure 1 is a central longitudinal section of a furnace and its electrical and mechanical connections and accessories; Fig. 2 is a diagrammatic view of a modification thereof, certain of the electrical and mechanical connections being omitted.

Referring to the drawings, A', A², A³ and A⁴ are tubes of conducting, non-magnetic or

only slightly magnetic material chosen to or made to resist a high temperature, preferably carbon with a few per cent. of carbids in it, such as is used for electrolytic work.

a², a², are radially arranged hollow carbon rods cemented into the respective tubes A', A², A³, and A⁴ by graphite cement and serving to conduct the electric current to said tubes, each of which is one of a pair of electrodes, but serving also as means of current-supply and as guides for carbon pencils or solid carbon rods a³ closely fitting into said hollow rods a². Such a pencil can be moved forward and backward and serves to strike an arc in starting the furnace.

B is a central electrode extending within and through the tube electrodes A', A², A³, and A⁴, between which tube electrodes and central electrode the arc is struck by pencils a³.

a⁴ is a shell of fire-brick or loose magnesia, outside of which is an external iron casing a⁵.

c is a solenoid surrounding the reaction chamber within the furnace and is separated from the external casing a⁵ by an asbestos layer a⁶.

The solenoid c, when continuous or single-phase alternating currents are used, is connected in series with the arc-current and in parallel with a rheostat, so that the magnetism may be regulated independently of the arc-current. When two-phase currents are used, one phase for the arc and the other phase for the solenoid, the rheostat is put in series with the solenoid. The former of these arrangements of circuits is illustrated in Fig. 1, where g represents a separately excited generator of either the direct current or single-phase alternating type, and i the rheostat.

The reaction chamber of the furnace is provided with a conduit d of refractory material for the gases to be treated, and a closed circuit of this conduit is completed by pipe d'. In a part of this circuit, such as pipe d', is provided a fan d² of refractory material with cooled axle bearings and driven from the outside. Through one of two openings, d³, d⁴, provided in the in-

closure of said circuit, new gas or vapor is added in continuous stream, while through the other opening on the opposite side of the circuit a corresponding volume 5 of gases or vapors escapes. The fan can be dispensed with when it is found sufficient that the particles of the gas or vapor pass the series of disks only once.

To start the furnace, the rods of cylinder 10 A^3 are pressed against rod B and at the same time current connection is made between these rods and the lower end of rod B , and then an arc is established by withdrawing the rods of cylinder A^4 , as described more fully in Patent 1,094,354, dated 15 April 26, 1914, granted to Erwin F. von Wilmowsky; Edwin J. Prindle, executor. Thereupon by withdrawing the rods of cylinder A^3 and severing said connection of 20 these rods with the lower end of rod B , another arc is established at the level of the rods of cylinder A^3 , while the pressure of the dynamo is increased at the same time by more than fifty volts, according to the 25 distance between the central rod B and the tubes or cylinders. These arcs will be extinguished repeatedly until the temperature is high. In this way a series of disks is gradually established between concentric 30 cylindrical surfaces, through which disks the charge is moved.

The disks can be formed according to the desired temperature of a vastly different current-density. If they are intended to 35 be of very low temperature comparatively, and the central carbon rod of a furnace intended for gases has *e. g.* one-half ($\frac{1}{2}$) inch diameter, the carbon tube inside one and one-half ($1\frac{1}{2}$) inches diameter, the area between the rod and the tube being therefore one and six-tenths (1.6) square inches, then an energy supply of about fifteen (15) amperes and forty-five (45) volts continuous current in a magnetic field of 150 ampere- 40 turns will give already a perfect luminous disk, while with alternating current about sixty (60) volts and fifty-five (55) amperes are needed, with 400 ampere-turns for the 45 solenoid. These figures depend upon the preparation of the carbon and above all 50 upon the temperature existing already in the furnace.

To reduce the temperature of the disk as far as possible, first the solenoid-current is 55 reduced, then the volts. To do this conveniently a dynamo with separately excited fields is used.

A modified and similar arrangement for the treatment of gases is shown diagrammatically in Fig. 2, the details of construction being omitted but these may be the same as shown in Fig. 1 or in the original application hereinbefore referred to, as far as applicable. In this figure A is an insulated tube, and B' , B^2 , B^3 are parts of

the central electrode. This furnace can be started without carbon rods by moving B^3 toward B^2 until it touches, and withdrawing and producing an arc at first between B^3 and B' . Thereafter when the electrode-distance increases and the current at last prefers to use the insulated outside tube A as part of its way, two disks are formed between B^3 and the tube, and between the tube and B^2 . And at last two or more disks are established in the same way by moving B' , between B' and the tube and between the tube and B^2 . It is clear from what has been said, how to arrange for a larger number of disks, when such larger number is desired.

In the operation of these furnaces, after the arc has been started, the effect of the solenoid is first to cause the arc to rotate. Should the arc be extinguished, the solenoid current is weakened and the arc again started. As soon as the furnace has reached a high temperature, a more or less regularly rotating arc is seen, *i. e.* a luminous, more or less spiral broad line, or lines, between some rotating, brightly incandescent spots on the electrodes. This rotating arc avoids overheating to a certain extent, but is for most purposes not a sufficient solution of the problem mentioned in the preamble. The magnetism, and at the same time the voltage of the main current, are now increased until the rotating arc is transformed into a homogeneous luminous disk, hereinbefore referred to as the "arc-disk" or the "disk." Thereby the highest temperature existing in the furnace is reduced considerably, though the supply of energy is increased, the heat being now uniform. The electric discharge in this form is perfectly steady and controllable. A homogeneous luminous disk stretches itself across the tube, making on the two electrodes rings of entirely uniform and moderate brightness. No rotation whatever is visible, and the electricity appears to stream simultaneously between said rings, not preferring at any one moment a special linear path. This disk, when only a few inches in diameter, is noiseless, except with alternating current, which besides requires, in order to form a disk, more amperes and more volts for the same apparatus. When the disk is once formed, any increase in current will increase the luminosity and the temperature, which latter can be regulated with precision by regulating the current-supply. When the central electrode is moved even considerably out of its central position the disk is not changed thereby in its appearance or uniform luminosity, and no motion in it is visible. When the magnetism is sustained and the current for the disk reduced, the disk is changed at last into a quick rotating arc emitting a roaring noise, even if less than

two inches in diameter. This is another striking difference between the disk and the rotating arc.

The simultaneous streaming of electricity mentioned above makes this furnace particularly fit to pass therethrough gases or vapors which are to be exposed to electrolytic and electro-synthetic forces or to be heated to a certain temperature favorable to a desired reaction. The feeding tube may be located adjacent the outlet tube so that the heat from the outgoing stream of gases is communicated to the fresh gas mixture. This may be done by dividing the feeding tube *e* shown in the original application above mentioned for treatment of solid materials, this tube being stationary instead of rotating.

In the following claims the word "arc-disk" will be used in place of what in the above specification is called simply "disk," the word "arc" designating any electrical discharge through a gas or vapor-space which is made conductive by heat, whatever its character and appearance may be.

I claim—

1. The process of treating mixed gases, comprising passing them repeatedly in contact with an electric arc.
2. In an electric furnace, the combination of a heating chamber, means for forming an arc therein, and means for causing gases to pass repeatedly through the heating chamber.
3. In combination, a furnace chamber in which reactions are caused to take place, means for producing an electric arc in said

chamber, a conduit circuit including said chamber, means to cause a circulation of gas through said circuit, and gas supply and gas outlet connections for said circuit.

4. In combination, a furnace chamber in which reactions are caused to take place, means to form an arc-disk in said chamber, a conduit-circuit including said chamber, means for causing the movement of gases within said circuit, and supply and outlet connections for said circuit on opposite sides of said arc.

5. In combination, means for producing a magnetic field, means for producing an electric arc within said field, means to supply alternating current to said magnetic field producing means, and means for repeatedly circulating gas through said field and in contact with said arc.

6. In combination, means for producing a magnetic field, means for producing a plurality of electric arcs influenced by said field and means for repeatedly circulating a gas past and in contact with said arcs.

7. In combination, means for producing a magnetic field, means for producing a plurality of electric arcs in series influenced by said field, and means for repeatedly circulating a gas past and in contact with said arcs.
